MACHINE FOR STACKING DRINKING CUPS

Eugene Conti, Jackson Heights, N. Y., assignor to Herz Manufacturing Corporation, a corporation of New York

Original application October 6, 1942, Serial No. 463,357. Divided and this application June 3, 1944, Serial No. 538,591

5 Claims. (Cl. 214—6)

1

The subject matter of this application is divided out of my co-pending application Serial No. 463,357, filed October 6, 1942.

This invention relates to a mechanism for stacking drinking cups of the open mouth type which cups may be made of paper or some functionally equivalent material.

An object of the invention resides in the provision of a mechanism for, and method of, stacking or nesting the formed cups in such manner that the stack will lie in a rectilinear position rather than in a curvilinear position to accomplish the advantageous results hereinafter pointed out.

A further object of the invention is to provide a mechanism for, and method of, positively moving the cups from a forming machine to their stacked positions.

Other objects of the invention will appear as this description progresses, and it is therefore unnecessary to here state them in detail.

In the drawings:

Figure 1 is a perspective view of one of the cups of the type to which this invention is directed.

Figure 2 is a view of several of the cups stacked.

Figure 3 is a sectional view of the stacking mechanism.

Figure 4 is a vertical sectional view of the stacking mechanism.

Figure 5 is a vertical sectional view taken at right angles to Figure 3; and

Figure 6 is a sectional view taken on line 6—6 of Figure 5.

In my above identified co-pending application I have disclosed the method and mechanism for forming cups of the type to which this invention is directed, and while it is unnecessary here to illustrate and describe that mechanism it is pointed out that the forming mechanism forwards the cups when formed directly and positively to the stacking mechanism, as will later be described.

Reference is now made to the drawings.

After each of the cups has been partly formed, that is, with its longitudinal edges sealed together and the bottom flap has had adhesive applied to it, the bottom flap is ready to be folded over so that the adhesive will adhere to the body of the cup and close its bottom. This closing is accomplished by a pair of pressure rollers 111, the upper of which is spring mounted and capable of vertical movement and the lower of which is driven by suitable means (not shown). These rollers are carried by an angular lever 112 pivoted at 113 and which carries a roller 114 on its lower

2

end. This roller cooperates with a cam 115 on a driven shaft 102. When the cup reaches a position in alignment with the space between the rollers 111, the lever 112 oscillates toward the bottom of the cup to fold the flap on the body of the cup and to exert pressure on the flap so that it is sealed and the bottom of the cup closed. The rollers 111 function to grip the cup between them.

Beyond the rollers 111 which feed the completed cups from the turret are two horizontal pairs of suitably driven spaced vertically arranged pulleys 116 and 117, around the pulleys of which pairs cooperating belts 118 and 119 are arranged so that their adjacent horizontal reaches 120 lie in contact and move in the same direction, i. e., away from the rollers 111 and at substantially the same speed. This movement of course is caused by driving the pulleys of the upper horizontal pair 116 in a counterclockwise direction and the pulleys of the lower horizontal pair 117 in a clockwise direction by a suitable mechanism.

As the completed cup is fed by the rollers 111 forwardly the leading edge is taken up by the reaches 120 of the belts and the cup is fed toward the delivery end of the machine, being carried between the reaches 120 of the belts with the seam of the cup lying longitudinally between these reaches and with the base or bottom of the cup forming the leading edge.

A cup positioning mechanism is located beyond the ends of the belts 118 and 119 and is adapted to receive the cups from these belts. This mechanism is illustrated in Figures 3, 4, 5 and 6. It includes a stationary support 121 (see Figures 4 and 5), having an opening 122 therein through which the cups are adapted to pass. An oscillating delivery head 123 is mounted on the support 121 and is held in place by a ring 124. This delivery head comprises a base portion and an extending reduced neck portion 125. The base is provided with an annular portion 126 which is supported in the support 121 on suitable bearing surfaces so that it may be oscillated. The base is also provided with a circular recess at 127 which is flared at 128. Additionally the base and neck portions are provided with slots 129 and 130 that extend at right angles to each other, as shown in Figure 12 and extend completely through the base and the neck portion longitudinally. The slots 129 and 130 in the base portion of the delivery head are enlarged as at 131 (see Figure 5) to receive the expanded edges of the cup, the expansion of which is due to the fact that the lateral edges, as indicated in Figure 2,

are preferably not creased but simply rolled and therefore of rounded circumferential contour. This delivery head is rotated or oscillated by means of a quadrant gear 132 the teeth of which intermesh with teeth 133 on the delivery head. This quadrant is pivoted at 134 and its oscillating movement is caused and controlled by a cam 135 which cooperates with a roller 136 on the quadrant and a spring 137 which holds the roller 136 in engagement with the cam 135. Thus, looking at Figure 5, the quadrant will be moved to the left by the cam 135 which will rotate the delivery head in a clockwise direction. The quadrant will be moved in the opposite direction to rotate the delivery head in a counterclockwise direction when the cam 135 moves to assume the position shown in Figure 5, under the influence of the spring 137.

This cam 135 is actuated by intermeshing gears 138, one being rigid with the cam and the other carried by a shaft 139.

In Figure 4 three successive positions of the cup are indicated in construction lines. These positions are designated respectively J, K and L. As a cup is being fed from the reaches 120 of the belts 118 and 119 it lies in the position J. From this position it is fed, by mechanism which will later be described, into the position K with its trailing edge 140 lying beyond the face of the ring 124. From this position K it is fed into the position L by a mechanism which will later be described and beyond this position into the receiver 141 in which it is stacked with other cups.

Referring now to the mechanism which moves the cups from the position J to the position K and directing attention to Figure 3, this mechanism includes a bell crank 142 which is pivoted on a stationary pivot at 143. On one arm of the bell crank a roller 144 is mounted, which roller rides upon and cooperates with a cam 145 on the shaft 139. On the end of the other arm of the bell crank a cup advancing finger 146 is pivoted at 147. This pivotal connection is such that frictional pressure will always be exerted on the advancing finger 146 to maintain it in the various positions into which it is moved. A pivoted arm 148 which is pivoted on a stationary pivot 149 is provided with a cam 150 connected with a rod 151. This rod carries a roller 152 which rides upon and cooperates with a cam 153 on the shaft 139 to move the lever 148 about its pivot 149.

I have described one advancing finger 146 and one lever 148 but it will be seen from Figure 4 that there are two such advancing fingers 146 and two such levers 148.

When the cup is in the position J in Figure 4 the toes 154 of the advancing fingers 146 lie behind the trailing edge of the cup, as illustrated in Figure 4, and in the position shown in Figure 3. The rotation of the cam 145 rocks the bell crank lever 142 about its pivot 143 (see Figure 3) to move the end of the bell crank lever, that carries the advancing finger, in a clockwise direction. This movement carries with it the advancing fingers and the toe portions 154 of the advancing fingers, engaging the trailing edge of the cup, push the cup into the position K (see Figure 4). The pushing of the cup beyond the base of the delivery head into this position K is made possible because of the presence of the recess 127 into which the toe portions of the advancing fingers move.

While one cup is being moved from the position J to the position K another cup is being advanced to the position J by the belts 118 and 119 so that

it is obvious that the toe portions 154 of the advancing fingers 146 must be moved out of the line of travel of the succeeding cup in order to prevent their engagement with the leading edge of the cup and their interference with the advance of the cup. As the advancing fingers 146 are moved rearwardly by the counterclockwise movement of the end of the lever 142 to which the advancing fingers are pivoted, pins 155 on the advancing fingers 146 engage the cams 150 on the levers 148. As the fingers continue to move to a retracted position the cooperating pins 155 and cams 150 depress the toe portions 154 of the advancing fingers 146 to positions out of the path of movement of the advancing cup.

After the toe portions have reached a position beyond the trailing edge of the cup when it lies in the position J tail portions 156 on the advancing fingers 146 engage abutments 157 so that the continued and final movement of the lever 142 causes the fingers 146 to move in a counterclockwise direction in Figure 6 to again move the toe portions 154 up behind the trailing edge of the cup in the position J. The cycle is then completed and the cup which at this time occupies the position J is then advanced to the delivery head.

In order that the cup may be removed from the delivery head into a receiver and there stacked I have provided a delivery plate 158 (see Figures 4 and 5) which is provided with two arms at 159 that are adapted to lie behind the trailing edge of the cup when it is in the position K so that the cup may be moved to the receiver by these arms.

This delivery plate is rigidly mounted on a slide 159' which is adapted to be reciprocated in the frame by the following mechanism. The slide carries a roller 160 (see Figure 6) with which a bell crank 161 pivoted at 162 cooperates. A cam roller 163 is mounted on this bell crank and cooperates with a cam 164. The contact between the end of the bell crank 161 and the roller 160 is maintained by a spring 165 and the contact between the cam roller 162 and the cam 164 is maintained by a spring 166. Thus the cam 164 acts through the lever 161 and the roller 160 to move the delivery plate 158 from a position adjacent the base of the delivery head to and beyond the position shown in Figure 4 of the drawing. As the cam rotates, however, the spring 166 returns the delivery plate from the position shown in Figure 4 to the initial position described, which position is illustrated in Figure 4 in construction lines and is designated by the reference character M. Thus the movement of the delivery plate 158 under the influence of the cam 164 moves the cup toward the receiver and this movement, being rapid, as the cup leaves the reduced neck portion 125 of the delivery head the cup is kicked into the receiver and stacked or nested with other cups that have previously reached the receiver.

It is here pointed out that when a cup is being moved into the delivery head, the arms 159 of the delivery plate lie in the dotted construction line position M shown in Figure 4 and in the position shown in Figure 5, thus covering the ends of the slot 120 but leaving the horizontal slot 129 free. It is into this slot 129 that the cup is fed.

After the cup reaches the position K (see Figure 4) where it lies horizontally in the slot 129 (see Figure 5) the quadrant 132 rotates the delivery head in a clockwise direction so that the

slot 129 is moved from its horizontal position to a vertical position such as occupied by the slot 130 in Figure 5. This partial rotation of the delivery head carries the cup with it so that the cup is moved from a horizontal position to a vertical position and the arms 159 of the delivery plate 158 lies behind the trailing edge of the cup so that when the delivery plate is advanced the cup will be pushed forwardly to the receiver.

As has been pointed out, the overlapping edges of the wings 5 and 6 of the cup, that is to say, the longitudinal seam of the cup lies between the belts 118 and 119 so that it is fed to the delivery head substantially coaxial with the head and with the seam downwardly.

Looking at Figure 5, when the slot 129 with the cup therein is moved to the vertical position, the seam of the cup will lie to the left of the vertical and in this position the cup is moved into the receiver. When, however, the delivery head with the next cup positioned therein is rotated in the opposite direction the cup, which is received by the slot 130 when it is in its horizontal position, is moved with the delivery head so that the seam of the cup lies to the right of the vertical and in this position it is moved into the stack and nested.

Thus the seams on the alternate cups will be on the opposite sides of the stack and the stack will therefore, and because of this alternate arrangement of the seams, assume a rectilinear rather than a curvilinear condition from which flow the advantages which have been heretofore pointed out.

In the drawings I have illustrated the cup as having the seam extending longitudinally or lengthwise thereof and parallel with the lengthwise axis of the cup. However, I wish it to be understood that when I refer to a longitudinal seam I am not confining myself to one that extends parallel to the lengthwise axis of the cup for indeed it may extend at an angle to the axis and even then not completely from the top to the bottom of the cup. The invention in some of its phases is still applicable to and contemplates the formation and stacking of the cup which has its seam extending more nearly crosswise than lengthwise of the cup.

While I have illustrated and described a particular machine as embodying one phase of my invention, and also detailed steps of the method, it is to be understood that I do not wish to be limited to the construction of the particular machine disclosed and described or to the detailed method except in so far as this is necessitated by the claims.

What I claim is:

1. In a cup forming machine including means for forming a series of cups each having a seam extending longitudinally on one side thereof, the combination of a cup stack receiver, means for positively moving the cups in succession into stacked nested relation in said receiver with the seams of alternate cups on opposite sides of the stack, means for positively delivering said series of cups into position to be engaged and moved by said cup moving means, said cup moving means including a rotatable head having cup receiving slots arranged in angular relation to each other, and passing longitudinally therethrough, means for rotating said head alternately in opposite directions to vary the angular position of successive cups carried thereby, and means operating after each rotation of said head for mov-

ing the successive cups positively from said head to form a stack of cups in said receiver.

2. In a cup forming machine including means for forming a series of cups each having a seam extending longitudinally on one side thereof, the combination of a cup stack receiver, means for positively moving the cups in succession into stacked nested relation in said receiver with the seams of alternate cups on opposite sides of the stack, means for positively delivering said series of cups into position to be engaged and moved by said cup moving means, said cup moving means including a rotatable head having slots arranged in angular relation to each other, and passing longitudinally therethrough to receive the cups from the delivery means, means for rotating said head alternately in opposite directions to vary the angular position of successive cups carried thereby so that the position of their seams is reversed in the receiver and to bring said cups into position to be delivered from said head, and means for thereafter moving the successive cups positively to form a stack in said receiver, said last mentioned means including a reciprocable delivery member having arms adapted to engage the trailing ends of the successive cups as the latter are in said delivery position.

3. In a cup forming machine including means for forming a series of cups each having a seam extending longitudinally on one side thereof, the combination of a cup stack receiver, means for positively moving the cups into stacked nested relation in said receiver with the seams of alternate cups on opposite sides of the stack, means for positively delivering said series of cups into position to be engaged and moved by said cup moving means, said cup moving means including a rotatable head having slots arranged in angular relation to each other, and passing longitudinally therethrough to receive the cups from the cup delivering means, means for rotating said head alternately in opposite directions to positively move the successive cups carried thereby into delivering position and so that the position of their seams is reversed, and means for thereafter moving the successive cups positively to form a stack in said receiver, said last mentioned means including a reciprocable delivery member having arms adapted to engage the trailing ends of the successive cups when in delivery position, said delivery means being actuated to move the successive cups into said rotatable head to such a degree that the trailing end of each successive cup lies beyond the starting position of the arms of said delivery member whereby said rotatable head may be rotated without the said arms interfering with the cup carried thereby.

4. In cup stacking mechanism for use with cup forming machines, or the like, which produce cups having a seam extending longitudinally on one side thereof, the combination of a cup stack receiver, means for feeding cups one after another and with said seams uniformly arranged in the same relation thereto, a rotatable cup holder having one end positioned and adapted to receive cups from said feeding means, means for alternately rotating said cup holder first in one direction and then in the opposite direction to change the angular position of cups delivered successively to said receiving end thereof, and means movable in relation to said rotatable cup holder toward said receiver and into engagement with a cup when in said changed angular position, to move cups so engaged into stacked relation in said receiver and with the seams of alternate

cups disposed on opposite sides of the resulting stack of cups.

5. In cup stacking mechanism for use with cup forming machines, or the like, which produce cups having a seam extending longitudinally on one side thereof, the combination of a cup stack receiver, a rotatable cup holder having intersecting cup receiving and guiding slots, means for feeding a cup into one of said slots while a cup in the other of said slots is being moved toward said cup stack receiver, and means for rotating said cup holder alternately in opposite directions to bring first one and then the other of said slots into operative cup receiving relation to said cup feeding means.
